CLAIM

The ornamental design for a package for an electric lamp, as shown and described.

DESCRIPTION

FIG. 1 is a rear, left side, perspective view showing our new design;

FIG. 2 is a top plan view thereof;

FIG. 3 is a front elevational view thereof;

FIG. 4 is a rear, left side elevational view thereof;

FIG. 5 is a rear, left side, perspective view showing a second embodiment of our new design;

FIG. 6 is a top plan view of the second embodiment of FIG. 5;

FIG. 7 is a front elevational view of the second embodiment; and,

FIG. 8 is a rear, left side, elevational view thereof.

FIG. 1

FIG. 2

FIG. 3

FIG. 4

FIG. 5

FIG. 6

FIG. 7

FIG. 8
